Primary Examiner — Dana L Meyrow(74) *Attorney, Agent, or Firm* — Leanne Taveggia Farrell; Westman, Champlin & Koehler, P.A.(57) **CLAIM**

The ornamental design for a bottle, as shown and described.

DESCRIPTION

FIG. 1 is a perspective view of a bottle showing our new design;

FIG. 2 is a side view thereof, the opposite side view, the front view and the rear view being identical;

FIG. 3 is a top view thereof;

FIG. 4 is a bottom view thereof; and,

FIG. 5 is a section view thereof.

The broken lines are included for purposes of illustrating portions of the bottle and form no part of the claimed design.

1 Claim, 4 Drawing Sheets(56)
